UNITED STATES PATENT OFFICE.

KRISTIAN MARIENTIUS PETERSEN, OF CHRISTIANIA, NORWAY.

STAMPING MACHINE.

Application filed November 6, 1923, Serial No. 673,164, and in Norway November 7, 1922.

The present invention relates to a machine for stamping, impressing or printing of characters, designs, patterns, ornaments &c. on metals, stone, wood, porcelain, paper 5 &c.

One object of the invention is to provide a machine of the type referred to, in which the stamps or matrices used for the stamping, impressing or printing may be easily 10 positioned accurately over the desired spot of the plate or the like to the stamped &c. by means of the said machine.

Another object is to provide means whereby by the stamping, impressing or printing 15 may take place in any desired direction on the plate or like in question.

Still another object is to provide means whereby the distance between the characters which are impressed or printed may be 20 easily adjusted, and also to provide means whereby the correct distance between adjacent characters is almost automatically chosen, notwithstanding the fact that alphabets &c. having characters of different types 25 and size may be used in one and the same machine.

The invention also includes a special type of stamps or matrices to be used in connection with the machine referred to.

30 Further features will appear from the following description and claims.

The accompanying drawings show one constructional form of a machine according to the invention, which machine is especially adapted for printing map designs.

Fig. 1 is an end view of the machine.

Fig. 2 is a side view thereof.

Fig. 3 is a side view of an adjusting mechanism for the support which carries the 40 press pistons.

Fig. 4 shows the same in front view.

Fig. 5 shows a side view of a modification of the adjusting mechanism, and

Fig. 6 is a front view thereof.

45 Fig. 7 shows still another modification of the adjusting mechanism.

Fig. 8 is a sectional view of the beam and the support, the press pistons being arranged radially in the holder and

50 Fig. 9 is a front view thereof.

Fig. 10 is a sectional view of the beam and the support, the press pistons being arranged axially in the holder and

Fig. 11 is a plan view thereof.

55 Fig. 12 shows a section through a holder

having radially disposed press pistons and Fig. 13 a corresponding section through a holder having axially disposed press pistons.

Fig. 14 is a sectional view of the press 60 pistons holder, showing the adjusting stamp or pin to be used at the initial adjustment.

Fig. 15 shows a section taken on line I—I in Fig. 14.

Fig. 16 shows a press piston in side view, 65 and

Fig. 17 shows the same seen from below.

With reference to Figs. 1 and 2 the legs 1 support a casing 2, the upper side of which is provided with longitudinal V-shaped 70 grooves 3, which are adapted to receive and guide correspondingly shaped ribs 4 on a sliding table 5. The said table is at the upper side thereof provided with a circular groove 6, which receives a rib or projection 75 7 on a working table 7, which is mounted on the table 5 and may be turned thereupon. The movement of the table 7 may be obtained by means of a hand wheel 8, which through a shaft 9 journalled in the table 5 80 and a worm 11 acts upon a worm wheel 10, which is secured to the lower side of the table 7.

The tables 5 and 7 may be imparted translatory movements on the casing 2 by means 85 of a hand wheel 12, the shaft 13 of which is journalled in the casing 2 and carries a gear 14 that meshes with a rack 15 arranged at the lower side of the table 5.

To each side of the casing 2 are, in a suitable manner, secured brackets 16, 17 which support a beam 18, that extends over the machine and carries and guides a support 19. This support carries a nut 20, through 90 which extends a screw-threaded bar 21, by 95 the manoeuvring of which the support 19 may be translated on the beam 18.

For the translation of the table 7 in the longitudinal direction of the casing 2, the shaft 13 is extended past the table, and is 100 journalled in a supporting member 22 secured to the bracket 17.

The shaft 13 carries at the end thereof a sprocket wheel 23 which may be driven, through a chain 24 from a sprocket wheel 105 25 carried on a shaft 26, which is journalled in supports 27 and 28 mounted on the beam 18. The shaft 26 is provided with a longitudinal wedge groove 29, which receives a correspondingly shaped wedge on a sleeve 30 110

provided with a hand wheel 31. The sleeve 30 is rotatably mounted in a bracket 32 secured to the support 19, and thus the sleeve 30 and the hand wheel 31 will accompany the support 19 when the same is moved along the beam 18. When the hand wheel 31 is rotated, the sleeve 30 will turn the shaft 26, which in its turn rotates the sprocket 25, and thus, through chain 24 and sprocket 23, rotates the shaft 13, which latter, by means of the gear 14 and the rack 15, moves the table either in one direction or the other.

The support 19 is provided with a fixed ring member 33. Figs. 8 and 9 on which is rotatably mounted a ring that carries the stamps. The last mentioned ring is kept in place on the ring member 33 by means of clamps 34 and screws 35. On the support are also formed brackets 36 and 37 respectively, the bracket 36 acting as a guide for a pin 38, the top end of which carries a roller 39, and the lower end of which is formed as or secured to a press plunger 40, which penetrates into a vertically arranged aperture in the ring member 33. Between the ring member 33 and a disc 41 on the press plunger, is mounted a helical spring 42, which acts to keep the press plunger in its upper position. The press plunger may be lowered by means of a lever 43 which is pivotally mounted on the bracket 37 and is provided with an eccentric portion 44, which, when the lever 43 is turned to the left (Fig. 8), acts against the roller 39, thereby pressing the same, and accordingly also the plunger 40, downward.

It should be noted, however, that the means for moving the press plunger downward may be of any other suitable type than those here described, which are shown only by way of example. Thus press screws, levers &c. may be used.

Figs. 10 and 11 illustrate another manner of mounting the stamp ring on the support 19. In a projection 45 on the support 19 is mounted a vertically arranged shaft 46, held in place by means of a nut 47. The shaft 46 carries a horizontally arranged disc or ring member, in which the stamps are arranged. The lever 43, which is provided with the eccentric portion 44, is pivotally mounted in ribs 48 arranged on the projection 45, which ribs are also provided with vertical slots 49 that receive the pin 50 which carries the roller 39, thus guiding the same and also the pin 38. A horizontal rib 51 situated between the ribs 48, has a vertical hole which guides the lower portion of the press plunger 40. In order that the press plunger 40, if desired, may be lowered without using the lever 43, the rib 51 is provided with a vertical slot through which extends a finger 52, which is secured to the plunger and may be pressed upon to lower the plunger.

In order to make the lowering of the plunger 40 still more easy, the plunger may be detachably secured (not shown) to the pin 38, whereby the plunger 40 may be lowered without the necessity of counteracting the pressure of the spring 42.

In Fig. 12 is shown a section through the ring which carries the stamps, these latter being radially movable as shown in Fig. 8. The ring designated generally at 100 is made up of three distinct rings 53, 54 and 55 respectively each provided with projections 56 or grooves, to adjust the position of the rings with respect to each other. These three rings are provided with radial holes 57 to receive the stamps 58. The diameter of the hole of the middle ring 54 is somewhat greater, thus providing space for the arrangement of a helical spring 59 around the stamp. The lower end of the spring 59 acts against the ring 55 and the upper end thereof against a pin 60, which is passed through the stamp 58. The ends of the pin 60 extend into vertical slots 61 arranged in the hole, whereby the stamp 58 is prevented from turning or rotating in the hole.

In Fig. 13 is shown a section through a stamp ring when arranged horizontally. The ring consists of two separate parts 62 and 63, which are provided with holes 57. The lower part of the hole in the part 62 has a greater diameter than the rest of the hole, to provide space for the spring 59 and transverse the pin 60. In this case the stamp is prevented from turning by means of a Woodruf wedge 60', which goes into corresponding wedge groove arranged in the side of the hole 57 in the part 63.

The stamp rings are arranged to receive an alphabet of capital letters and one alphabet of small letters and further the ring is provided in line with each stamp 58, with a markation stating the letter, number or character of the stamp in question, and also with a markation line which, when a stamp 58 is placed directly below the press plunger 40, corresponds with a markation on the projection 33. Thus the desired stamp may readily be brought in correct position below the plunger. In order to make it more easy for the operator to move the stamp ring by means of his fingers, the said ring may be provided with suitable cavities or be knurled in well known manner.

In each stamp ring is also arranged a special stamp or pin 64 (Figs. 14-15) the lower end of which is shaped to form a fine point. This stamp, the object of which will be described later, and which will be denoted as adjusting pin, is eccentrically mounted and longitudinally movable in a sleeve 65, which latter is mounted eccentrically and rotatably in a sleeve 66, the last named sleeve being rotatable in the stamp ring. The sleeves 65 and 66 are, both of them, at the

lower ends thereof, provided with flanges 68 and 67 respectively. The peripheries of the said flanges are provided with holes, and by placing a suitable pin or key in these holes 5 the sleeves may be turned, whereby the position of the adjusting pin 64 may be changed in relation to the axis of the opening 57. The upper part of the pin 64 carries a head 69 and between this head and 10 the sleeve 65 is placed a helical spring 70, which presses the pin 64 upwardly or inwardly. The holes in the flanges 67 and 68 are made accessible, and the light is given 15 access to the pin 64, by cutting away suitable portions of the ring members 54 and 55 adjacent the lower end of the pin 64.

The support 19 and the stamp ring must be sufficiently displaced laterally for stamping of the next letter in the word to be 20 stamped. To this effect the end of the shaft 21 carries a gear 71 (Figs. 3 and 4), which through a gear 72, adjustably mounted on a member 73, acts upon a gear 74 rotatable on a shaft 75 that is journaled in a bracket 25 secured to the frame 16. On the shaft 75 is also pivotally mounted an arm 77, which carries a spring pressed pawl 78, which is provided with a handle 79 and may mesh with the gear 74.

30 On the frame 16 is demountably secured a circular shell or hoop 80, the centre of which coincides with the centre of the shaft. In this hoop 80, and vertically to the longitudinal direction of the arm 77, there are arranged 35 pins 82 having heads 81, which pins through the action of springs 83 are normally held within the hoop 80. When it is desired to displace the support 19 a certain distance, that pin 82 which corresponds to such distance (indicated by the numbers on the hoop 40 80) is pressed toward right (Fig. 4) against the action of the spring 83, whereby the arm 77, when moved to move the gear 74, will about with its abutment 84 against the said pin 82. Thus the movement of the pawl 78 45 is limited to that number of teeth on the gear 74, which are necessary to impart the desired movement to the shaft 21 and thereby to the support 19. If, in some instances, 50 the displacement of the support determined by the said pins 82, is to be increased or decreased, the gear 71 may be removed and replaced by a smaller or a greater gear. Very long displacements of the support 19, which 55 for instance occur during the initial adjusting of the same in the correct position over the table, are carried out by first displacing the gear 71 on the shaft so as to bring the same out of mesh with the gear 72, where- 60 upon the shaft 21 is turned by means of a crank 86 with a handle 85, carried at the end of the shaft 21.

In Figs. 5 and 6 is shown a modification 65 of the means for displacement of the support 19. The hoop 80 is provided along its

periphery, with notches 87 which coact with a spring pressed pawl 89 that is provided with a handle 88. The said pawl is situated in an arm 90 mounted on the shaft 21, which arm also has an extension 91 that extends closely over the periphery of a ratchet wheel 92 secured to the shaft 21. On the shaft 21 is also pivotally mounted an arm 93 that carries a spring pressed pawl 95 for coaction with the ratchet wheel 92. On the beam 18 is in a suitable way secured a bracket 96 which limits the rearward movement of the arm 93.

When the support 19 is to be displaced by means of this mechanism, the arm 90 with 80 its pawl 89, is swung down to the proper notch in the hoop 80. The extension 91 thus becomes placed over a certain spot of the ratchet wheel 92, and when the arm 93 is swung forward the pawl 95 will, by reason 85 of the wedge shaped section of the extension 91, be moved on to and on the outer side of the said extension. When the pawl has thus engaged the extension, the arm 93 is swung backward, and the pawl will slide down the 90 extension and engage the ratchet wheel 92. Thus the action of the pawl 95 is limited to the desired number of teeth.

In Fig. 7 is shown still another modification 95 of the mechanism for displacing of the support 19. Here the arm 90 is omitted, only one arm being used. The arm 93 carries a plate spring 97 the free end of which is V-shaped, as are also the notches 87 in the hoop 80. When the arm 100 93 is moved the plate spring therefore successively passes down into the notches, thus indicating the distance which the arm 93 has been moved. The outer end of the shaft or screw 21 carries a hand wheel 99 105 with handle 98, to be used during the initial placing or adjusting of the support 19.

The letters of an alphabet are of different widths, and with regard to the said widths the letters may be classified in six or seven classes. Thus it is necessary that the support may easily be displaced a corresponding number of different distances, when the machine is used for printing of, say, a name. This is achieved by proper arrangement of the notches 87, so that when the arm 93 is moved to any one of the said notches and then back to its rear position, the ratchet wheel 92 and accordingly also the shaft 21 will be turned to such an extent that the support is displaced a distance which corresponds to the width of that class of letter which the said notch represents.

If the pins 82 or notches 87 are designated 115 by the numbers 1-7 for instance (see Figs. 4, 6 and 7) the ring member which carries the stamps may also be provided, directly below the letters which indicate the different stamps, with numerals that state to which 120 125 130

class (as to width) the letter in question belongs. (Figs. 9 and 10). Thus, when a letter is placed below the press piston 40, it is also at the same time seen how far the 5 arm 93 is to be moved over the hoop 80 in order that the support 19 shall be displaced the correct distance to ensure that the letter, when stamped or printed, shall get the correct position in relation to the letter 10 last stamped or printed.

For alphabets having letters of different types and sizes, the class arrangement (the notches or pins) of the hoop 80 must be different. For this reason the hoop 80 is 15 made demountable, so that when a new stamp ring is inserted, also the corresponding hoop 80 may be replaced for that previously used. To avoid mistakes the different stamp rings and their corresponding hoops may be provided with corresponding 20 designation characters. The size of each class on the hoop 80 includes, of course, not only the actual width of the class of letters in question, but also the distance which 25 should be obtained between adjacent letters when printed or stamped.

In order to be able to obtain, if desired, a greater and smaller distance between adjacent characters, special hoops 80 may be 30 used, or each hoop 80 may be provided with a special notch or pin so arranged that the same in each case will add (or subtract) a certain distance to (from) the normal one determined by the usual notches or pins.

35 The adjusting pin 64 shown in Figs. 14 and 15 serves to provide a means whereby the first letter of a word to be printed will be printed in exactly the desired position. The point of the pin 64 is so situated that 40 it exactly corresponds with the intersection of say the right side of each letter space and the imaginary base line thereof. During the adjusting of the support of the machine, in order to place the support in 45 correct relation to the piece to be printed upon, the said support is adjusted until the point of the pin 64, when depressed, coincides exactly with that place at which it is 50 desired that the above defined point of intersection shall be placed. Then the support is in correct position and the printing operation may begin.

In order that it shall not be necessary to 55 manufacture a special type of adjusting pin arrangement for each type of alphabets the said pin is made adjustable, as previously mentioned by means of the eccentric sleeves. Thus it is only necessary to print one suitable letter with the alphabet in question, and then adjust the pin 64 to correct position in the stamp ring, by turning the sleeves 65 and 66 until the point thereof 60 when depressed, will cover the point of the section mentioned above.

65 In order that each character shall be

stamped to an equal depth, each stamp 58 (Figs. 16 and 17) carries at the end thereof, the character matrice in the shape of an extension on the stamp. Thus the stamp rod 58 proper will abut against the plate in 70 which the character is impressed, and limit the movement of the stamp, no matter which is the pressure exerted on the press piston.

Having now particularly described and ascertained the nature of my said invention, 75 and in what manner the same is to be performed, I declare that what I claim is:

1. A machine for stamping or impressing characters and the like on metal and other material including a frame, a beam mounted 80 on said frame, a table movable on said frame in a direction of right angles to said beam, an upper table rotatable on the first mentioned table, a support reciprocally mounted on said beam, and stamps mounted 85 in said support.

2. A machine for stamping or impressing characters and the like on metal and other material including a frame, a beam mounted 90 on said frame, a table movable on said frame in a direction of right angles to said beam, an upper table rotatable on the first mentioned table, a support reciprocally mounted on said beam, and stamps mounted 95 in said support, means for adjusting the support along said beam, said means including a screw and nut device.

3. A machine for stamping or impressing characters and the like on metal and other material including a frame, a beam mounted 100 on said frame, a table movable on said frame in a direction of right angles to said beam, an upper table rotatable on the first mentioned table, a support reciprocally mounted on said beam, and stamps mounted 105 in said support, a shaft rotatably mounted on said frame, means carried by and movable with the support for rotating said shaft, and means connecting said shaft with said table for adjusting the latter. 110

4. A machine for stamping or impressing characters and the like on metal and other material including a frame, a beam mounted on said frame, a table movable on said frame in a direction of right angles to said beam, an upper table rotatable on the first mentioned table, a support reciprocally mounted on said beam, and stamps mounted 115 in said support, a shaft journaled in said frame, a member carried by said support and connected with said shaft for rotating the latter, and adjustment means for the first mentioned table and means for connecting said shaft with said adjusting means. 120

5. A machine as claimed in claim 1 characterized by the provision of means for turning the upper table about its axis of rotation. 125

6. A machine as claimed in claim 1 characterized by the provision of means for ad- 130

justing the first mentioned table upon the frame, and means for turning the upper table about its axis of rotation.

7. A machine as claimed in claim 3 characterized by the provision of means operable independently of said shaft for adjusting the first mentioned table.

8. A machine as claimed in claim 1 characterized by the provision of a shaft 10 journalled in said frame, an operating member for said shaft slidably and non-rotatably mounted thereon, means connecting the operating member with the support for movement with the latter, means for adjusting said first mentioned table, said adjusting means including a shaft, and means transmitting the movement of the first mentioned shaft to the second mentioned shaft.

9. A machine as claimed in claim 1 characterized by the provision of operating 20 means for the stamps.

10. A machine as claimed in claim 1 characterized by the provision of a ring carried by the support and constituting a

mount for the stamps, and a pointed adjusting pin mounted in said ring, means for adjusting said adjusting pin with respect to said ring and means normally retaining the pin in inoperative position. 25

11. A machine as claimed in claim 1 characterized by the provision of means for adjusting said support, said adjustment means including a screw shaft, means for rotating said screw shaft step by step, and means for adjustably limiting the extent 30 of each rotary movement of the screw shaft.

12. A machine as claimed in claim 1 characterized by the provision of means for adjusting said support, said adjustment means including a screw shaft, means for 35 rotating said screw shaft step by step, and means for adjustably limiting the extent of each rotary movement of the screw shaft, and means for limiting the adjustment of the last mentioned means. 40 45

In testimony whereof I affix my signature.

KRISTIAN MARIENTIUS PETERSEN.
